Inventor:

Christian Peter Jensen.

UNITED STATES PATENT OFFICE.

CHRISTIAN PETER JENSEN, OF KROPP, NEAR SCHLESWIG, GERMANY.

DOORCHECK.

Application filed September 8, 1925, Serial No. 55,018, and in Germany April 6, 1925.

This invention relates to a device for deadening the slamming of doors and the like and consists in the provision of an arched blade spring arranged so that the arc projects from the door jamb and takes the thrust of the door, one end of the spring being secured to the jamb and the other supported in the direction of the chord by a coil spring which is guided in a socket. is guided in the thimble 3. The two springs together produce an efficient and noiseless buffer whereby the door, on being slammed, will be effectively checked and the shock absorbed. The device is easy to make and can easily be applied to any existing door jamb. Two or more checks of this kind may be used for each door.

10 Fig. 1 of the accompanying drawings represents a longitudinal section of the device, and

Fig. 2, is a front view of the same.

Fig. 3 is a view showing the device in use,
15 and

Fig. 4, a cross-sectional view of the device.

The door check is composed of a blade spring 2 which is arched and arranged so that the arc projects from the door jamb and takes the thrust of the door when the latter is slammed. The spring, one end of which is secured to the door jamb, straightens out under the impact and it is supported in the direction of its chord by a coil spring 4 which is guided in a socket formed by a thimble 3. Preferably the spring 2 and the thimble 3 are both secured to a metal mount 1 which is L-shaped in cross-section, the metal mount and socket being let into the door jamb so that only the spring arc projects from the jamb through a slot made in the metal mount. The free end of the spring 2 is fitted with a spherical head 5 whereby it bears against the spring 4 and whereby it

is guided in the thimble 3. The two springs together produce an efficient and noiseless buffer whereby the door, on being slammed, will be effectively checked and the shock absorbed. 35

The device is easy to make and can easily be applied to any existing door jamb. Two or more checks of this kind may be used for each door. 40

I claim:

1. A door check comprising an arched blade spring arranged so as to face the door with its arc and so as to be straightened under the impact, one end of the spring being rigidly and the other slidably supported, a coil spring arranged so as to support the slidably end of the blade spring in the direction of its chord, a socket guiding the coil spring, and a spherical head connected to the slidably head of the blade spring for guiding the latter in said socket. 45 50 55

2. A door check comprising a metal mount of L-shaped cross-section formed with an elongated slot, an arched blade spring secured at one end to the metal mount and arranged so that its arc projects through the slot in the latter, a spherical head secured to the free end of the spring, a thimble containing said head and secured to the metal mount so as to guide the head in the direction of the chord of the blade spring, and a coil spring arranged in said thimble as a support for said head. 65
